UNITED STATES PATENT OFFICE.

CHARLES S. BEEBE, OF RACINE, WISCONSIN.

FANNING-MILL.

SPECIFICATION forming part of Letters Patent No. 280,897, dated July 10, 1883.

Application filed December 7, 1881. (No model.)

To all whom it may concern:

Be it known that I, CHARLES SETH BEEBE, of Racine, in the county of Racine, and in the State of Wisconsin, have invented certain new and useful Improvements in Fanning-Mills; and I do hereby declare that the following is a full, clear, and exact description thereof.

My invention relates to fanning-mills; and it consists in certain improved mechanism wherewith the shoe that carries the screen is supported and shaken, as will be fully described hereinafter.

In the drawings, Figure 1 is a perspective view of a machine embodying my invention with a part of the top of it broken away. Fig. 2 is a side view of the same.

The main object of my invention is to provide in one machine mechanism for hanging the shoe, so that it can be adjusted to shake bodily from side to side or to oscillate on an arc of a circle. The former is styled in the trade the "body" shake, and the latter the "flirt" shake. Hence in this application I show and describe the devices for producing both the body and flirt shake, because all my machines are made to embody both; but I only claim the construction necessary for the body shake at the present time, and reserve the mechanism for producing the flirt shake as the subject of a future application.

A is the casing of a fanning-mill, and A' the shoe. I provide the shoe on each side with lugs J and f to receive hangers B and K, and on one side of the shoe, in addition to the lugs J f, I provide the shoe with an elbow-plate, C, and connect it by a staple, a, with the bell-crank lever D, which is swiveled in lug e, attached to the frame.

The fan-wheel is revolved by any convenient means and is connected to the lever D by a rod, E. A bar, G, is fastened to the shoe A' at its front and midway between its sides, and the front end of this bar projects forward and up against the top of the casing A and into a staple, H, which is provided with a groove, I, and the ends of which staples are screw-threaded and project up through the top of the casing to receive set-nuts F F. To give the

shoe the body shake, set-nuts F are loosened to allow the staple H to drop down away from 50 the top of the casing, as shown in Fig. 1. This leaves bar G free to slide from one end to the other of the staple H. The hangers B are then caught over lugs J, and hangers K in lugs f. The shoe will now be supported evenly 55 on each side of the elbow-plate C, and, as it is connected with the fan-wheel crank by elbow-lever D and rod E, each revolution of the crank will throw the shoe from one side to the other of the casing and back again, and in these reciprocations the front and rear of the shoe will both travel together at right angles to the length of the casing. Now, to change the shake from body to flirt, the hangers B are withdrawn from the lugs J, so as to let the 60 weight of the body of the shoe rest entirely upon the hangers K and bar G, and the staple H is tightened up against the casing, as shown in Fig. 2, so as to confine the end of bar G in groove I, which groove, while it is sufficiently 65 large to permit the bar to oscillate in it, will hold it against lateral play. Therefore, if the fan-wheel be turned it will cause the rear of the shoe to vibrate in the arc of a circle of which a vertical line drawn through the groove 70 I of the staple H is the center, and thus will be produced the flirt shake.

The hangers B, I have shown swiveled in inclined bearings in the lugs c d, attached to the top and sides of the frame of the mill. The 80 hangers K are suspended from lugs b, secured to the rear end of the frame.

What I claim as new, and desire to secure by Letters Patent, is—

The combination, in a fanning-mill, of the 85 casing, screen-shoe, independent hangers B and K, lugs c, J, d, b, and f, plate C, bell-crank lever D, and crank-rod E, substantially as set forth.

In testimony that I claim the foregoing I 90 have hereunto set my hand this 4th day of November, 1881.

CHARLES SETH BEEBE.
